UNITED STATES PATENT OFFICE.

HAROLD JAMES MANNING BAKER, OF PORT TOWNSEND, WASHINGTON.

LUGGAGE-CARRIER FOR BICYCLES.

SPECIFICATION forming part of Letters Patent No. 595,517, dated December 14, 1897.

Application filed March 13, 1897. Serial No. 627,361. (No model.)

To all whom it may concern:

Be it known that I, HAROLD JAMES MANNING BAKER, of Port Townsend, in the county of Jefferson and State of Washington, have 5 invented a new and Improved Luggage-Carrier for Bicycles, of which the following is a specification.

My invention is an improvement in the class of bicycle luggage or package carriers which 10 are constructed of wire and adapted to be attached to the handle-bar of the machine.

The object of my invention is to provide a carrier which shall be simpler and cheaper in construction, also smaller or more compact 15 than others of its class, so that it may be conveniently carried in a coat-pocket, and which may be attached and detached by an easy and rapid manipulation, yet will retain its place on the machine without the aid of supplemental fastenings. To these ends I have adopted the construction shown in accompanying drawings, in which—

Figure 1 is a perspective view of a bicycle-head with my invention applied thereto. Fig. 25 2 is a perspective view of my invention. Figs. 3, 4, and 5 are perspective views illustrating the manner of applying the luggage-carrier to a bicycle-head.

My improved device A is formed of a spring-30 wire or metal strip and is distinguished by three principal bends or open loops—to wit, two vertical parallel end loops a and a central horizontal loop b, which is in a plane below the others, a, as shown. The terminal 35 portions or arms of the end loops a are pendent and extend below the plane of the central loop b, being provided with hooks a' for convenient attachment of cords used to suspend luggage or other articles.

It will be noted the vertical end loops a and b are connected by means of arms extending horizontally between them, and which, when the device is applied to a bicycle, lie behind and beneath the handle-bar.

When the device A is applied to a bicycle

B, (see Fig. 1,) the central loop b receives and embraces the head c and passes around the front side thereof, while the end loops a pass over the handle-bar d at contiguous points and their hooked ends a hang below the same, as shown. In order to thus apply the carrier A, one of the end loops a is passed over one end of the handle-bar d, as shown in Fig. 3. Then the device is pushed along, so that the other end loop a also embraces the handle-bar d, as in Fig. 4, whereupon the device is pushed farther, till the left hook passes beyond the head c, when the device is turned over, Fig. 5, whereby the central loop b passes into place and embraces the head c and bears against the front side of the same. The device A will of itself maintain this position and support packages or luggage attached to its hooks a'.

It will be observed the end loops a serve to 65 support or suspend the device A from the handle-bar, and the central loop b prevents rotation of the device on the handle-bar.

In order to prevent rattle or clatter of the carrier A with the machine, an elastic strap 70 or band C, Fig. 1, may be attached to one of the hooks a' and passed behind the bicycle-head c and connected with the other hook a', as shown.

What I claim is—

As an improved article of manufacture, the wire luggage-carrier hereinbefore described, the same having a central horizontal bend or open loop, for embracing the bicycle head or post, arms extending laterally from such loop, 80 and the vertical loops a, a, formed at the ends of said arms and projecting forward, so as to hang on the handle-bar, and their terminal portions extending downward below the middle loop, and having hooked ends a', as shown. 85

HAROLD JAMES MANNING BAKER.
